No. 36,719.

Patented December 29, 1903.

UNITED STATES PATENT OFFICE.

JOHN H. GAVIN, OF CHICAGO, ILLINOIS, ASSIGNOR TO L. WOLFF MANUFACTURING COMPANY, OF CHICAGO, ILLINOIS, A CORPORATION OF ILLINOIS.

DESIGN FOR A SHOWER-BATH FIXTURE.

SPECIFICATION forming part of Design No. 36,719, dated December 29, 1903.

Application filed September 5, 1903. Serial No. 172,171. Term of patent 14 years.

To all whom it may concern:

Be it known that I, JOHN H. GAVIN, a citizen of the United States, residing in Chicago, in the county of Cook and State of Illinois, 5 have invented a new, original, and ornamental Design for Shower-Bath Fixtures, of which the following is a specification, reference being had to the accompanying drawings, forming part thereof.

o The accompanying drawings, forming a part of this specification, show at Figure 1 a front elevation, at Fig. 2 a side elevation, and at

Fig. 3 a top or plan view, of a shower-bath fixture embodying my new, original, and ornamental design.

What I claim as new, and desire to secure by Letters Patent, is—

The ornamental design for a shower-bath fixture as shown.

JOHN H. GAVIN.
